UNITED STATES PATENT OFFICE.

SWITS CONDÉ, OF OSWEGO, NEW YORK.

DESIGN FOR A KNIT FABRIC.

SPECIFICATION forming part of Design No. 12,762, dated February 14, 1882.
Application filed December 12, 1881. Term of patent 7 years.

To all whom it may concern:

Be it known that I, SWITS CONDÉ, of Oswego, in the county of Oswego, in the State of New York, have invented new and useful Improvements in Design for Knit Fabric, of which the following, taken in connection with the accompanying drawing, is a full, clear, and exact description.

The annexed drawing represents a section of knitted fabric embodying my design, said design consisting in the following novel arrangement of stripes of different shades and widths, to wit: first, a wide mottled stripe, a, then a narrow plain dark stripe, b, then another wide mottled stripe, a, then a narrow plain light stripe, c, then a narrow mottled stripe, d, then another narrow plain light stripe, c, then beginning again with a wide mottled stripe like the first, and continuing with the succeeding stripes in the order aforesaid, all of said stripes being straight and parallel, substantially as set forth and shown.

What I claim is—

The design for knit fabric, consisting in the arrangement of the following stripes, to wit: first, a wide mottled stripe, a, then a narrow plain dark stripe, b, then another wide mottled stripe, a, then a narrow plain light stripe, c, then a narrow mottled stripe, d, then another narrow plain light stripe, c, then beginning again with a wide mottled stripe like the first, and continuing with the succeeding stripes in the order aforesaid, all of said stripes being straight and parallel, substantially as set forth and shown.

In testimony whereof I have hereunto signed my name and affixed my seal, in the presence of two attesting witnesses, at Oswego, in the county of Oswego, in the State of New York, on this 1st day of November, 1881.
